ATTORNEY

UNITED STATES PATENT OFFICE.

JOSEPH PELNAR, SR., OF DEERFIELD, KANSAS.

BOLSTER STAKE.

1,420,691.

Specification of Letters Patent. Patented June 27, 1922.

Application filed August 21, 1920. Serial No. 405,043.

To all whom it may concern:

Be it known that I, JOSEPH PELNAR, Sr., a citizen of the United States, residing at Deerfield, in the county of Kearny and State 5 of Kansas, have invented new and useful Improvements in Bolster Stakes, of which the following is a specification.

This invention relates to bolster stakes for wagons and has for an object the provision 10 of a stake which is strong and durable in construction, easily manufactured and readily repaired.

Another object is the provision of a bolster stake which is formed from a single strip 15 of metal and bent to provide contacting parallel members having ring receiving eyes and attaching ears, the construction being such that the stake may be bent without breaking, but will resist considerable strain.

20 With the above and other objects in view, the invention further includes the following novel features and details of construction, to be hereinafter more fully described, illustrated in the accompanying drawings and 25 pointed out in the appended claims.

In the drawings:—

Figure 1 is a fragmentary view of one end of a bolster with the improved stake applied.

Figure 2 is a detailed perspective view of 30 the stake removed from the bolster.

Referring specifically to the drawings wherein like characters of reference denote corresponding parts, the reference character 10 indicates a bolster of the usual or any 35 preferred construction, while the improved stake is indicated at 11.

The stake is formed of a single strip of metal and bent centrally to provide parallel contacting members 12 and 13. The portion 40 of the stake which connects the members 12 and 13 is bent to provide an eye 14, while the member 12 is bent intermediate its length to provide an eye 15. The eyes 14 and 15 receive stake rings 16 as is usual in devices 45 of this character. The opposite ends of the metal strip are bent substantially at right

angles to provide outwardly extending attaching ears 17 which are located at the end of the stake opposite the eye 14. Apertures 18 are provided in the ears 17 for the 50 passage of fastening devices for securing the stake to the bolster.

The invention provides an exceedingly strong and durable stake which is easily attached to a bolster and while the members 55 12 and 13 are not secured together by welding or any other means, one member acts to strengthen the other so as to resist bending. Should such bending occur however, the stake may be easily straightened without the 60 aid of a mechanic.

The invention is susceptible of various changes in its form, proportions and minor details of construction and the right is here- 65 in reserved to make such changes as properly fall within the scope of the appended claims.

Having described the invention what is claimed is:—

1. A bolster stake formed from a single 70 strip of metal bent centrally upon itself to provide parallel contacting members, the connected portion of said members being formed into an eye, a second eye located intermediate the ends of the stake and formed 75 by bending the said member outwardly into substantially semi-circular form, apertured securing ears formed by bending the extremities of the strip outwardly and rings located within the eyes. 80

2. A device of the class described comprising parallel contacting members formed of a single strip of metal and provided with spaced transverse openings, a plurality of rings extending through said openings, and 85 attaching ears extending at right angles from opposite sides of said members and having openings formed therein.

In testimony whereof I affix my signature.

JOSEPH PELNAR, SR.
